MULTIPLE LETTER TRAY

Donald F. Lewis, Golden, Colo., assignor of one-half to Peter Pepper Products, Inc., Lomita, Calif., a corporation of California

Application April 27, 1959, Serial No. 55,663

Term of patent 14 years

(Cl. D74—9)

Figure 2 is a side elevational view of said multiple letter tray; and

The ornamental design for a multiple letter tray, substantially as shown.
